WHEEL CENTER

Joseph R. May, Chatham, and Donald F. Morgan,
Bloomingdale, N.J., assignors to Amerace Corpora-
tion, New York, N.Y.

Filed Feb. 14, 1974, Ser. No. 442,661

Term of patent 14 years

Int. Cl. D12—16

U.S. Cl. D12—211

Figure 1

Figure 3

Figure 2

FIG. 1 is a front elevational view of a wheel center showing our new design;

FIG. 2 is a rear elevational view thereof; and

FIG. 3 is a sectional view thereof taken along the line 3—3 of FIG. 1.

The broken lines in the drawing are for illustrative purposes only.

We claim:

The ornamental design for a wheel center, substantially as shown and described.
